UNITED STATES PATENT OFFICE.

CLEMENS METTE, OF HANCOCK, MICHIGAN.

SLEIGH.

SPECIFICATION forming part of Letters Patent No. 280,499, dated July 3, 1883.
Application filed October 17, 1882. (Model.)

To all whom it may concern:

Be it known that I, CLEMENS METTE, of Hancock, Houghton county, Michigan, have invented a new and Improved Sleigh, of which 5 the following is a full, clear, and exact description.

This invention consists of an improved beam and knee connection with the runner for greater flexibility on uneven roads, the arrangement 10 being contrived with special reference to economy in construction and reliability of the said flexible connection, all as hereinafter more fully described.

Reference is to be had to the accompanying 15 drawings, forming part of this specification, in which similar letters of reference indicate corresponding parts in all the figures.

Figure 1 is a side elevation of a bob-sled constructed in accordance with the said invention, a part being sectioned. Fig. 2 is a plan view, also with a part in section; and Fig. 3 is a section through the beam and knee, showing the arrangement of the flexible joint.

A represents the runners, B the beam, and 20 C the knees. The knees and beam are framed together in the usual manner; but instead of framing the knees into the runner I arrange them to rest upon the surface of the runner at the end, making the said end a little convex, 25 as shown at D, and to secure the beam to the runner I employ the metal knee-bolts E and stay-bars F, the bolts and the bars being rig-

idly attached together at G, the bolts also being attached to the plate H, bolted to the runner, and the stay-bars bolted to the runner at I. The beams and the knees are grooved for the bolts E, and also for concave liners J, of metal, fitted in the grooves behind the bolts E and secured to the wood, so as not to have any play therein. The said liners are fitted snugly to the bolts E along the middle, but they are slack at the ends and along therefrom toward the middle sufficiently to allow the beams and the runners to rock the one upon the other, thus providing for the flexibility of the joints by a substantial arrangement not liable to wear out unduly, nor to break.

Having thus described my invention, I claim as new and desire to secure by Letters Patent—

The combination, with the beams B and knees C, resting with convex ends upon the surface of the runner, of the knee-bolts E and stay-bars F, attached together at G, the plate H, attached to the runner, and the liners J, the latter being fitted closely at the middle, but loosely at the ends, in the bolt-grooves of the beams and knees, whereby the beams may rock upon the runners and a flexible jointing be produced, as set forth.

CLEMENS METTE.
